UNITED STATES PATENT OFFICE.

EZRA E. BATHROW, OF PRINCE ALBERT, SASKATCHEWAN, CANADA.

SQUARE.

No. 874,653.

Specification of Letters Patent.

Patented Dec. 24, 1907.

Application filed March 10, 1906. Serial No. 305,373.

To all whom it may concern:

Be it known that I, EZRA E. BATHROW, a subject of the King of England, residing at Prince Albert, Saskatchewan, North West Territory, Dominion of Canada, have invented a new and useful Square, of which the following is a specification.

This invention relates to the squares and similar implements employed by carpenters, builders and other mechanics, and has for its object to produce an implement of this character in which the blades may be folded into parallel relations when not in use, and extended and automatically held in extended position when required.

With these and other objects in view which will appear as the nature of the invention is better understood, the invention consists in certain novel features of construction as hereafter fully described and claimed.

In the accompanying drawings forming a part of this specification and in which corresponding parts are denoted by like designating characters, is illustrated the preferred form of the embodiment of the invention capable of carrying the same into practical operation.

In the drawings.—Figure 1 is a side view of a portion of the improved device including the elbow and portions of the blades, from one side. Fig. 2 is a similar view from the opposite side. Figs. 3 and 4 are perspective views of the two portions of the blades, disconnected. Fig. 5 is a detail edge view of the joint between the blades.

The improved device is more particularly applicable to the ordinary carpenters' square consisting of one relatively long and wide blade called the "blade", and one relatively narrow and shorter blade called the tongue, the two members being suitably graduated into inches and parts of inches and other graduations.

The blade is generally twenty four inches long and the tongue from twelve to sixteen inches long.

The blade 10 in the improved device is provided with a projection 11 one half the thickness of the blade and extending in the direction of the tongue 12, while the inner portion of the tongue is cut away to form the plate 13 one half its thickness and overlapping the projection 11 of the blade.

The overlapping portions are united by a pivot 14, with the free end of the projection 11 curved at 15 concentric to the pivot, and

the shoulder 16 formed between the body of the tongue 12, and the plate 13 correspondingly curved as shown.

The free curved end 17 of the plate 13 engages the shoulder 18 formed between the projection 11 and the blade 10.

The projection 11 is provided with a lug 19 adapted to fit into a socket or recess 20 in the tongue 12, while the plate portion 13 is provided with a similar lug 21 for engaging a socket or cavity 22 in the blade 10, the lugs and recess being inclined at their engaging faces, and with square shoulders 23—24 at the roots of the lugs, for bearing against the correspondingly formed ends of the respective lugs which engage them.

The lugs 19 and 21 thus form stops to prevent the tongue 12 from swinging beyond a position square with the blade 10, while the inclined faces of the lugs engaging the correspondingly inclined faces of the recesses, form an effectual locking means against lateral movement between the parts.

The shoulder 23 and 24 add materially to the stability of the joint, by bearing a large share of the friction and relieving the relatively thin terminals of the lugs from a corresponding portion of the strain.

The projection 11 is formed with a recess 25 into which the point 26 of the shoulder portion 16 of the tongue 12 enters when the blades are placed in parallel positions, as indicated by dotted lines in Fig. 1.

Formed through the blade 10 adjacent to the recess 22 is a slot 27 in which a spring 28 is secured by a screw pin 29, the terminal of the spring operating in a recess 30 extending entirely through the blade, the blade also having a thumb recess or depression 31 to enable the operator to manipulate the spring.

The plate 13 is provided with a recess 32 which comes opposite the recess 30 in the blade 10 when the blade and tongue 12 are in operative position, as in Fig. 1, with the inner end 33 of the recess 32 inclined at a less angle than the sweep of the spring 28, so that as the latter attempts to move away from its recess 30, it will impart a strong pressure against the inclined face 33 and firmly lock the two members 10 and 12 in their right angled position. The spring, thus imparts a constant strain upon the plate 13, and any wear which may occur between the two parts, is taken up by the constant pressure of the spring. Thus all tendency to

rattling or looseness between the parts is obviated.

The spring 28 is supported by an additional screw pin 34 at the bend in the same.

5 With a device thus constructed, the tongue member 12 of the square may be folded into position parallel to the blade 10, when the implement is to be shipped, or disposed in the tool chest or other receptacle, and quickly 10 extended into operative position when required.

Having thus described the invention what is claimed is:—

1. In an implement of the class described, the blade portion having a projection extending at right angles therfrom and of less thickness than the same and with a lug extending from its free end and a recess in the blade at the inner end of the 15 projection, the tongue portion having a plate at one end less in thickness than the tongue and overlapping said projection and pivotally united thereto, said plate having a lug for bearing within the recess of said 20 blade and said tongue having a recess for receiving the lug of said projection, and means for locking said projection and plate in position.

2. In an implement of the class described, 30 the blade portion having a projection at one end with a lug extending therefrom and inclined at one side and a recess in the blade formed with one inclined side, a tongue portion having a plate at one end overlapping 35 said projection and pivotally united.

thereto, said plate having a lug for bearing within the recess of said blade and inclined to correspond therewith and said tongue having a recess for receiving the lug of said projection and inclined to correspond thereto, and means for locking said projection and plate in position. 40

3. In an implement of the class described, the blade portion having a projection at one end, the tongue portion having a plate at 45 one end overlapping said projection and pivoted thereto and with a recess having an inclined end, and a spring carried by said blade and disposed with its free end bearing against the inclined end of said 50 recess.

4. In an implement of the class described, the blade portion having a projection at one end and an aperture partly in the blade and partly in the projection and a slot extending from the aperture, the tongue portion having a plate at one end overlapping said projection and pivoted thereto and with a recess having an inclined end, and a spring secured in said slot and bearing at 55 its free end against the inclined end of said recess.

In testimony that I claim the foregoing as my own, I have hereto affixed my signature in the presence of two witnesses.

EZRA E. BATHROW.
